UNITED STATES PATENT OFFICE

169,904

REENTRANT AND DIRECT DIFFRACTION LOUD-SPEAKER HORN

Louis S. Hoodwin, Bridgman, Mich., assignor to
Electro-Voice, Incorporated, Buchanan, Mich.

Application May 31, 1952, Serial No. 19,976

Term of patent 14 years

(Cl. D26—14)

To all whom it may concern:

Be it known that I, Louis S. Hoodwin, a citizen of the United States, residing at Bridgman, county of Berrien, Michigan, have invented a new, original, and ornamental Design for a Reentrant and Direct Diffraction Loud-Speaker Horn, of which the following is a specification, reference being had to the accompanying drawings, forming a part hereof.

Figure 1 is a perspective view of a reentrant and direct diffraction loud-speaker horn embodying my new design;

Figure 2 is a front view;

Figure 3 is a side view;

Figure 4 is a top view; and

Figure 5 is a view partially in cross-section to show with greater clarity the configuration of the horn.

The dominant features of my design reside in those portions shown in full lines.

I claim:

The ornamental design for a reentrant and direct diffraction loud-speaker horn, as shown and described.

LOUIS S. HOODWIN.
